UNITED STATES PATENT OFFICE.

ELMER R. EDSON, OF PORTLAND, OREGON.

RAILWAY ROADBED AND TRACK CONSTRUCTION.

Application filed April 18, 1927. Serial No. 184,686.

My invention relates to my United States Patent Number 1,612,271 issued to me under date of December 28, 1926.

This invention further relates to United States patent applications, filed concurrently herewith, and issuing as Patent 1,669,741, May 15, 1928, for a switching device, and Patent 1,669,742, May 15, 1928, for a railway switch.

10 The primary object of my present invention consists in providing road bed and track for railways wherein relatively high speeds are required, and consists in providing suitable means for maintaining the vehicle to be propelled along the track in intimate relationship with the track structure, the same consisting primarily of a ballasted railway of ties having superposed thereon a fabricated metal base of structural members to 20 which a railway rail is attached by any suitable fastening means, one flange of the rail projecting sufficiently to permit of an engagement of an antiderailment wheel thereunder, thus providing for two flanged wheels 25 engaging the rail, one upon either side, thus making possible high rates of speed and reducing the possibilities of derailment to a minimum by engaging each rail upon oppositely disposed sides thereof.

30 A further object of my invention consists in providing simple and efficient means of connecting the rail with the fabricated metallic support thereunder, in a manner to permit of the replacement of the rail members without the necessity of removing the fabricated support associated therewith.

35 A still further object of my invention consists in providing means to maintain the drive wheels of the vehicle in intimate relationship with the rail and further providing an outwardly disposed flange on the under side of the rail with which an antiderailment flanged wheel may be made to engage and to cooperate with the driving and supporting wheel of the vehicle.

40 And still further objects of my invention consist in utilizing in so far as possible standard shapes of approved design, and construction.

45 With these and incidental objects in view, the invention consists in certain novel features of construction and combination of parts, the essential elements of which are set forth in the appended claims, and a preferred form of embodiment of which is hereinafter shown with reference to the draw-

ings which accompany and form a part of this specification.

In the drawings:—

Fig. 1 is a top plan view, partially in section, of the assembled units.

Fig. 2 is a sectional end view, taken on line 2—2 of Fig. 1, looking in the direction indicated.

Fig. 3 is a fragmentary enlarged, end section view, of the fabricated base showing the same adapted to a masonry or concrete substructure.

Like reference characters refer to like parts throughout the several views.

I preferably form my substructure of railway ties 1, which are of the standard form and in place and alignment. I place thereupon a fabricated structural metallic base composed of longitudinal beams 2 and 3, the bases of which rest upon the ties and are secured thereto by any suitable fastening means, as by railway spikes. Cross members 4 and 5 maintain the longitudinal members in spaced relationship. The same may be made of special design having outwardly disposed end flanges 6 and 7, and be secured to the longitudinal members by suitable fastening means, as by rivets 8, or the same may be bent or formed at right angles, as 80 illustrated at 9 in Fig. 1, to form a foot thereupon that is at right angles to the body of the cross tie members and adapted to engagement with the web of the longitudinal beam. Where a specially rigid 90 construction is required, the same may have flanges disposed at either side of the cross web and having a row of fastening elements disposed at either side thereof. The head of the longitudinal members 2 and 3 is preferably formed of unequal legs 10 and 11 and supported thereupon is a ball rail 12, having an outwardly disposed leg 13, terminating in a ball 14 on the outer end. The rail and the longitudinal members are secured together by means permitting the removal of the rail from the beam as by bolts 15 and 16.

It is desirable that the ball 14 be disposed far enough from the end of the flange or leg 11 to permit of the passage of the flanged wheel 17 with a clearance 18 between the inner wall of the flanged wheel and the outer end of the leg of the upper flange 11 of the beam. The support and the driving wheel are illustrated in dotted position at 19 in Fig. 2, with the flange of the wheel here

shown as being disposed on the inner side of the ball 20 of the rail. The flange 21 of the wheel 17 engaging the ball 14 of the rail prevents the flanged driving and supporting wheel from rising sufficiently from the ball rail to permit of the disengagement of the supporting and driving wheel from the track, which makes possible a higher rate of speed than if the lower guidewheel were not associated therewith. In Fig. 3, I have shown a masonry base upon which the longitudinal structural members are resting, which will permit of high speeds. This form of construction may be found desirable over that of the wooden ties, as illustrated in Fig. 1.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow:

What I claim is:—

1. In a device of the class described, the combination of a structural road bed sub-structure composed of longitudinal beams spaced apart throughout their longitudinal alignment substantially the gauge of the track by cross struts secured to the web of the beams by suitable fastening means, and a railway rail superposed and secured upon each longitudinal beam, said rail being composed of a ball section and a base section and a web disposed therebetween, said base being composed of two legs of unequal length and one of said legs terminating on its outer end in a ball like shape.

2. In a device of the class described, the combination with a road bed substructure composed of longitudinal beams spaced apart substantially the gauge of the railway

and cross struts having flanged ends secured to the web of the longitudinal beams, of a rail disposed upon each of the longitudinal beams, and said rail having an outwardly projecting base portion terminating in an enlarged oval shaped edge substantially as described.

3. In a device of the class described, the combination of a substructure composed of fabricated longitudinal beams spaced apart substantially the gauge of the railway, cross struts having flanged ends secured to the web of the longitudinal beams, and a rail superposed upon each longitudinal beam, said rail having unequal legs composing its base and one of said legs terminating in a rounded edge.

4. In a device of the class described, the combination with a base or supporting structure composed of two parallel spaced beams, including spacing means therefor, of a rail secured upon each beam, each rail being formed with a ball tread, a supporting web, and two oppositely projecting legs or flanges of unequal width forming the base of said rail, the wider of the two flanges having an enlarged reinforcing portion upon and continuous with its upper outer edge, and projecting beyond the aforesaid beam to admit of the travel of a guard wheel upon its under surface substantially as described.

5. In a device of the class described, the combination with a base or supporting structure composed of two parallel spaced beams, including spacing means therefor, of a rail secured upon each beam, each rail being formed with a ball tread, a supporting web, and two oppositely projecting legs or flanges of unequal width forming the base of said rail, and the wider of the two flanges projecting beyond the aforesaid beam to admit of the travel of a guard wheel upon its under surface substantially as described.

ELMER R. EDSON.
